United States Patent

Des. 239,398
Patented Mar. 30, 1976

239,398

ARM CURL EXERCISING MACHINE

Robert Clarke, Pacific Beach, Calif., assignor to Paramount Health Equipment Corp., Los Angeles, Calif.

Filed June 24, 1974, Ser. No. 482,100

Term of patent 14 years

Int. Cl. D21—02

U.S. Cl. D34—5 K

FIG. 1.

FIG. 2.

FIG. 1 is a right front perspective view of an arm curl exercising machine showing my new design; and

FIG. 2 is a left rear perspective view thereof.

I claim:

The ornamental design for an arm curl exercising machine, as shown.
